UNITED STATES PATENT OFFICE.

DANIEL N. AVEY AND GUY T. HASTINGS, OF BUTLER, PENNSYLVANIA.

METALLIC RAILWAY-TIE.

SPECIFICATION forming part of Letters Patent No. 739,637, dated September 22, 1903.

Application filed July 25, 1903. Serial No. 168,955. (No model.)

To all whom it may concern:

Be it known that we, DANIEL N. AVEY and GUY T. HASTINGS, citizens of the United States, residing at Butler, in the county of Butler and State of Pennsylvania, have invented certain new and useful Improvements in Metallic Railway-Ties; and we do declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to new and useful improvements in metallic railway-ties; and it consists in the provision of a hollow metallic tie-boxing provided with downwardly extending flanges to securely hold the tie from longitudinal movement and in the provision of clamping means for holding rails to the boxing.

The invention consists, further, in various details of construction and in combinations and arrangements of parts, which will be hereinafter fully described and then specifically defined in the appended claims.

Our invention is illustrated in the accompanying drawings, in which similar letters of reference indicate like parts in the views, in which—

Figure 1 is a top plan view of a tie, showing means for holding the rails thereto. Fig. 2 is a central longitudinal section through the tie and the clamping means. Fig. 3 is a detail view showing the means for clamping the rails for holding the same to the boxing or tie.

Reference now being had to the details of drawings by letter, A designates a hollow tie having an aperture A¹ in its top and an opening A² in the bottom thereof, the ends of said opening A² terminating in flanges A³, which project at right angles from the tie and are adapted to form anchorage means for the tie to prevent the same from movement when embedded in the ballast of a railway. Integral with or secured to the top of the tie are stationary curved lugs B, designed to engage over the flange of a railway-rail, each of said lugs co-operating with a movable clamping member C on the opposite flange of the rail to hold the latter to the tie. Each of said

movable clamping members C has a shank portion extending through an aperture in the top of the tie and having a slot adapted to receive a wedge-shaped member D. The upper end of each wedge-shaped member when inserted in the slot of the shank portion of the clamping member contacts with the under surface of the top of the tie, and the inner end of each clamping member has threads which are adapted to engage threads in the apertures formed in the ends of the turnbuckle E, whereby as said turnbuckle is rotated in one direction the two wedge-shaped members will be drawn toward each other, thereby causing the movable clamping members to be drawn down securely against the flanges of the rails. The reverse movement of the turnbuckle will cause the wedge-shaped members to be thrown in the opposite direction, which will release the clamping members.

From the foregoing it will be observed that by the provision of a tie embodying the features of our invention the latter will be securely held from lateral or longitudinal movement by reason of the flanges on the under side thereof, while the rails will be securely held to the tie and clamped or released by means of the turnbuckle mechanism, thereby making a simple and efficient tie, to which rails may be easily and quickly applied.

While we have shown a particular detailed construction of apparatus illustrating the features of our metallic tie and rail-fastener, it will be understood that we may make alterations in the details of the same without departing from the spirit of the invention.

Having thus fully described our invention, what we claim as new, and desire to secure by Letters Patent, is—

1. A hollow railway-tie having fixed lugs adapted to engage the flanges of rails, movable clamping-jaws passing through the top of the tie, wedge-shaped members engaging slots in said members, and a turnbuckle having threaded engagement with the ends of said wedge-shaped members, whereby the latter may be drawn against the flange of a rail, as the turnbuckle is rotated, as set forth.

2. A hollow metallic railway-tie having an aperture in its top and bottom, flanges at the ends of the aperture in the bottom of said

tie, fixed lugs on the top of the tie, clamping-jaws extending through apertures in the tie, wedge-shaped members passing through elongated slots in said members and adapted to frictionally engage the upper surface of the top of a tie and draw said members securely against the flanges of a rail as the wedge-shaped members are moved longitudinally toward each other, and a turnbuckle having 5 threaded apertures in its ends engaging the 10

threaded ends of said wedge-shaped members, as set forth.

In testimony whereof we hereunto affix our signatures in presence of two witnesses.

DANIEL N. AVEY.
GUY T. HASTINGS.
